UNITED STATES PATENT OFFICE.

LELAND F. BURNHAM, OF PITTSBURGH, PENNSYLVANIA, ASSIGNOR TO R. D. NUTTALL COMPANY, A CORPORATION OF PENNSYLVANIA.

TROLLEY.

Application filed January 13, 1922. Serial No. 529,046.

To all whom it may concern:

Be it known that I, LELAND F. BURNHAM, a citizen of the United States, and a resident of Pittsburgh, in the county of Allegheny and State of Pennsylvania, have invented a new and useful Improvement in Trolleys, of which the following is a specification.

My invention relates to current collectors and particularly to means for mounting a plurality of contact devices upon a single supporting member.

My invention is designed especially for employment in connection with trolley busses or trackless trolley vehicles wherein contact members or current collectors are mounted for engagement with a pair of trolley wires. When such collectors are mounted upon a single pole, provision must be made to permit the vehicle to deviate from its normal path of movement, while, at the same time, insuring that the current collectors remain in engagement with their respective trolley wires.

The object of my invention is to provide an improved and simplified form of multiple-contact structure whereby engagement between the contact members and the trolley wires may be effectively maintained, notwithstanding deviations in the path traveled by the vehicle upon which the contact members are mounted, and to provide means whereby the electrical circuit through the vehicle will not be interrupted, even though the direction of travel of the vehicle be reversed.

In the accompanying drawings,

Figure 1 is a view, partially in front elevation and partially in section, of a current collector and supporting means therefor, which I employ;

Fig. 2 is a plan view thereof,

Figs. 3 and 4 are plan and side elevational views, respectively, of the swivel member which I employ,

Figs. 5 and 6 are plan and side elevational views, respectively, of one of the supporting arms.

Figs. 7 and 8 are plan and side elevational views, respectively, of the supporting arm for the other current collector; and

Fig. 9 is a plan view showing the form of knuckle which I employ for each of the two current collectors.

A trolley pole 10, only a portion of which is shown, is mounted upon a swivel base on

the roof of a vehicle (not shown) and is normally biased upwardly to maintain the current collectors in engagement with a pair of trolley wires, in the usual manner.

The pole 10 carries, at its upper end, a polehead 11 that is provided with a perforated extension 12 through which the shank 13 of a swivel member 14 extends. The swivel member 14 is maintained in place by means of a nut 15 and a spring 15a located between the nut and the underside of the extension 12. The spring serves to maintain close-fitting engagement between the swivel member and the pole head 11 and to compensate for wear which occurs between the frictional surfaces of the swivel member 14 and the extension 12 of the pole head 11.

The swivel member 14 is provided with a pair of upstanding arms 16 that are perforated for the reception of a bolt or shaft 17 that extends therethrough.

An arm 19, that is shown more clearly in Figs. 5 and 6, is provided with square shank portions 20 that fit between the upstanding portions 16 of the swivel member 14 and are provided with a hole 21 through which the bolt 17 extends to maintain the arm 19 in position for pivotal movement about the bolt 17 as an axis. Bushings 20a, of insulating material, surround the shank portions 20 of the arm 19.

The arm 19 is provided with a hole 24, that extends vertically therethrough, for the reception of a pin 25 that serves to support a knuckle member 26 for pivotal movement about a pin 25 as an axis. The knuckle 26 is tapped, at its outer end, (Fig. 9) for the reception of the threaded end of a shaft member 28 that serves to support a trolley wheel 29 which co-operates with a trolley wire 30.

At the other side of the pivot 17, I provide an arm 31. This arm is provided with extensions 32 and 33 (Figs. 7 and 8) that are recessed intermediate their ends to conform to the contour of two sides of the bushings 20a that surround the arm 19.

A pair of cover plates 35 are provided with recessed portions corresponding to those of the extensions 32 and 33 of the arm 31. By clamping the cover plates 35 to extensions 32 and 33, in the manner shown in Fig. 1, by means of a series of bolts 37, the arms 19 and 31 are maintained in rigid relation to each other and, consequently, are

pivots movably, as a unit, about the pin 17. The bushings 20a insulate the arm 31 from the arm 19 and the shaft 17.

The arm 31 is provided with perforations 5 through which a pin 39 extends, for pivots movably supporting a knuckle member 40, in the same manner as the knuckle 26 is supported by the pin 25 of the arm 19. The arm 40 is tapped for the reception of a shaft 10 41 that supports a trolley wheel 42 which operates with a trolley wire 43.

A spring conducting member 44 is provided between each of the trolley wheels 29 and 42 and its respective knuckle for 15 more readily conducting the current.

The arms 19 and 31 are each provided with a leaf spring 46 of the U shape that is secured in place in the arms by means of screws 47. The springs 46 are provided 20 with extensions that lie along the vertical sides of the knuckles 26 and 40, respectively, and normally serve to yieldingly maintain the knuckles in parallelism with their supporting arms.

25 The knuckles 26 and 40 and the arms 19 and 31 are each provided with holes into which pins 45 may be placed, as shown more clearly in Fig. 2, in order to prevent the knuckles 26 and 40 from moving about the pivots 29 and 30, respectively, under certain conditions of operation.

30 Current from the trolley wheel 29 may flow through the conducting member 44, knuckle 26, arm 19, swivel 16, pole head 11 and the pole 10. The arm 31, being insulated by the bushings 20a, the return circuit will be through a flexible connector 49 that leads to the vehicle, plates or brush members 52 and 53, conductor 50, the shaft 41, conducting member 44 and the trolley wheel 42.

35 A pair of plates 51 of micarta, or other insulating material, are mounted upon the extension 12 of the pole head 11 concentrically of the shank 13 of the swivel 16, and a metal plate 52 is secured to the upper side 45 of the disk-like members 51. Another metal plate 53 is secured to the under side of a pair of insulating disks 54 that are also mounted concentrically of the shank 13, and this upper group of plates 53 and 54 turn with the 50 swivel 16 about its axis 13.

From the foregoing, it will be seen that the current collectors 29 and 42 may have 55 rotative movement, in a vertical plane, about the shaft 17 as an axis. A projection 55 is secured to the underside of each of the knuckles 26 and 40 for engagement with a plate 56, of insulating material, that is secured to an extension 57 of the swivel member 14 to limit the rocking movement of the current collectors 29 and 42 about the axis 17. If desired, the wheels 29 and 42 may be insulated from each other by making the knuckle 40 or the arm 21 of insulating material.

It will also be apparent that the collectors 29 and 42 are independently rotatable in a horizontal plane about the pins 25 and 39, respectively, as axes, or that the collectors may be maintained in rigid alignment transversely of the trolley pole, by means of the locking pins 45.

During the operation of the vehicle, should one of the wires 30 or 43 occupy a higher horizontal plane than the other of 75 said wires, the upward tension exerted upon the pole will cause the current collectors 29 and 42 to move about the pivot 17, thus insuring that the current collectors will at all times be maintained in operative engagement with their respective wires, regardless of the differences of the height of 80 said wires.

It will be further observed that, should the vehicle be forced to detour from its normal path of travel beneath the trolley wires, the support upon the pole head may tend to turn diagonally of the trolley wires and thereby cause the wires to bind themselves between the flanges of the wheels 29 and 42 90 or to be moved out of the space between the flanges. The pins 25 and 39, however, permit the wheels 29 and 42 to swivel about such vertical pivots sufficiently to accommodate themselves to the misalignment between 95 the pole-head structure and the trolley wires, and, consequently, to maintain proper engagement with the trolley wires.

The brush members 52 and 53 permit an uninterrupted flow of current through the 100 conductors 49 and 50, throughout a complete turning movement of the vehicle.

Various modifications may be made without departing from the spirit and scope of the invention, as defined in the accompanying 105 claims.

What I claim as my invention is:

1. The combination with a trolley pole, of a pair of current collectors supported thereby in transversely spaced relation and each mounted for independent movement about a vertical axis, and means for providing pivotal movement of said collectors on their common transverse axis.

2. The combination with a trolley pole, of a pair of current collectors supported thereby, and mounted for independent rotative movement about vertical axes, and means for yieldingly maintaining the current collectors in alignment transversely of the trolley 120 pole.

3. The combination with a trolley pole, of a pair of current collectors supported thereby, in laterally spaced relation, means for permitting relative movement of the current collectors in a horizontal plane, and means for normally maintaining the current collectors in lateral alignment.

4. The combination with a trolley pole, of a swivel member carried thereby, a pair of 130

- current collectors supported by the swivel member, one of the collectors having electrical connection therewith and the other of the collectors being insulated therefrom, a 5 conductor supported by the pole, and a brush connection between the other insulated current collector and the said conductor.
5. The combination with a trolley pole, of a pair of current collectors supported thereby, one of the collectors being insulated from the pole and the other collector having electrical connection therewith.
- 10 6. The combination with a trolley pole, of a pair of current collectors supported thereby for pivotal movement, one of the collectors having electrical connection with the trolley pole and the other collector being insulated therefrom, a conducting member supported by the pole and means whereby the current collectors may rotate about the said 15 pivot, without interrupting the flow of current through said collectors.
- 20

In testimony whereof, I have hereunto subscribed my name this 6th day of January 1922.

LELAND F. BURNHAM.
